UNITED STATES PATENT OFFICE.

WILLIAM R. PARKINSON, OF CENTRALIA, ILLINOIS.

LIFE-BOAT.

1,129,718.

Specification of Letters Patent. Patented Feb. 23, 1915.

Application filed August 19, 1914. Serial No. 857,551.

To all whom it may concern:

Be it known that I, WILLIAM R. PARKINSON, a citizen of the United States, residing at Centralia, in the county of Marion and 5 State of Illinois, have invented new and useful Improvements in Life-Boats, of which the following is a specification.

This invention relates to life saving boats, the main object of the invention being to 10 provide a collapsible unsinkable life boat embodying internally controlled propelling means, means for supplying ventilation to the interior of the boat without danger of admitting water, and also means for reliably 15 balancing the boat when afloat or preserving the equilibrium thereof.

With the above and other objects in view, the invention consists in the novel construction, combination and arrangement of parts, 20 as will be hereinafter more fully described, illustrated and claimed.

In the accompanying drawings:—Figure 1 is a perspective view of the collapsible frame of the boat, omitting a portion of the 25 flexible covering. Fig. 2 is a view of said frame when collapsed or folded. Fig. 3 is a vertical cross section through the boat showing the propelling means. Fig. 4 is a detail sectional view of one of the ventilation tubes. Fig. 5 is a detail vertical sectional view of the head covering hood and the clamping means therefor. Fig. 6 is a detail view showing another form of door or hatch for the boat. Fig. 7 is a perspective view of the boat when fully covered. Fig. 8 is a bottom plan view of Fig. 4. Fig. 30 9 is a detail plan view of the flexible apron.

The life boat contemplated in this invention comprises, in the preferred embodiment 40 thereof, a collapsible frame embodying a cubical central portion A and front and rear substantially wedge-shaped portions B and C.

The central section of the boat comprises 45 the two oppositely arranged sets of top and bottom longitudinal bars 1 and 2, and the vertical bars designated generally at D each comprising an upper section 3 and a lower section 4 which are pivotally connected together at 5 and which are pivotally connected at 6 and 7 to the extremities of the top and bottom side bars 1 and 2, respectively. The two sides of the central part 50 of the frame hereinabove described are connected at top and bottom by front and rear cross bars 8 and 9, respectively.

Each of the front and rear wedge-shaped frames B and C comprises the upper and lower converging side bars 10 and 11, the end cross bar 12 to which the bars 10 and 11 are terminally pivoted, and a substantially horizontal distending bar designated generally at E, the same comprising two interfitting and telescopic sections 13 and 14 adapted when drawn outward to the limit, 60 to be held against moving inwardly by means of a spring catch 15 adapted to be manipulated by hand to release the sections 13 and 14 when the frame is to be collapsed.

When the frame as a whole is completely 70 extended or expanded as shown in Fig. 1, the central portion A thereof is held by means of diagonal spreader braces 16 and 17 which are pivotally connected at the points 7 to the remainder of the frame and 75 which are detachably fastened to the upper ends of the vertical bars D preferably by means of pins 18 carried by the extremities of the bars 16 and 17 and insertable through properly located holes in the uprights D. 80

The whole frame herein described is covered with a sheathing of flexible water- and air-proof material such as canvas properly treated, the same being designated at F, said covering or sheathing being fastened to the 85 appropriate bars of the collapsible frame in any convenient or preferred way. Beneath the bottom of the boat is an equilibration weight 20 which is shown as connected to the bottom of the boat by means of chains, 90 cables or other flexible connections 21.

Access is had to the interior of the boat by means of a door or hatch 22 hinged to one of the top bars of the boat as shown at 23 and being fastened down by means of 95 clamps or thumb screws 24. It is preferred to secure a rubber joint strip around the edges of the hatch 22 so as to make a watertight joint with the top of the deck of the boat when said hatch is closed. If desired, 100 the hatch 22 may be provided with a transparent panel 25 of glass, for example for observation purposes. It is, however, preferred to form a circular opening 26 in the hatch 22 to receive the marginal edge of the 105 disk-shaped apron 27 of a head covering hood 28 as shown in Fig. 5 and in connection with said hood, a clamping ring 29 is employed, the same being pivotally connected at 30 to the hatch and provided opposite the pivot 30 with a stem 31 which is connected to one arm of an operating lever 110

32 fulcrumed on a bracket 33 on top of the hatch 22. To the other arm of the lever 32 is attached an operating rod 34 extending through a hole in the hatch and provided 5 interiorly of the boat with a handle 35. This enables the clamping ring 29 to be opened and closed to release or fasten the apron 27 of the head covering hood 28.

A folding seat 36 is arranged within the 10 central portion of the boat and pivotally connected at 37 to the boat frame, such seat being adapted to fold through an arc of 90 degrees so as to permit the frame of the boat to be folded from the position shown 15 in Fig. 1 to the position shown in Fig. 2.

Ventilation tubes 38 extend through the top or deck of the boat and have U-shaped or recurved terminal portions which face downwardly and contain check valves 39 20 which allow air to freely enter the boat through said ventilation tubes and yet exclude water in case the boat should overturn.

The propelling means comprises a pair of cup-shaped paddles 40 located on opposite 25 sides of the central portion of the body and carried at the free ends by a pair of arms 41 connected to the opposite extremities of a common crank shaft 42 which passes through openings in the sides of the frame 30 and is formed with a central operating crank handle 43 which enables the propelling blades or paddles to be operated from the interior of the boat.

Any desired number of boats hereinabove 35 described, when collapsed, as shown in Fig. 2 may be carried on a vessel for use in times of emergency and disaster, the boat being constructed with a view to simplicity and rapid manipulation. When the boat is fully 40 closed and sealed, it is practically unsinkable, it is maintained in an upright position by means of the equilibration weight, the interior of the boat is properly ventilated and the boat may be propelled by externally 45 arranged propellers which are operable from the interior of the boat. If desired, the boat may be provided with a steering rudder 44 the post 45 of which is provided with a cross head 46 from which operating 50 ropes 47 extend into the interior of the boat. In some cases it may also be desirable to construct the boat in rigid or non-collapsible form but ordinarily it is preferred to make the boat collapsible for the sake of 55 compactness in storage and transportation.

I also prefer to employ a flexible waterproof apron or neck piece 48 within the hood 28 as illustrated in Fig. 5, said apron being shown in plan view in Fig. 9. The 60 apron is adapted to fit around the neck of

the wearer and is formed with a neck encircling hem 49 in which is placed a draw string 50 adapting the apron to be closely drawn and confined around the neck to prevent entrance of water at such point.

65

What I claim is:—

1. A collapsible boat comprising a substantially cubical center section and wedge-shaped fore and aft end sections jointed to said center section, all of said sections being composed of bars having a jointed connection with each other and together forming a skeleton frame, a flexible water tight cover inclosing said frame, and a hatch providing for ingress and egress to and from the interior of said boat.

70

2. A collapsible boat comprising a substantially cubical center section and wedge-shaped fore and aft end sections jointed to said center section, all of said sections being composed of bars having a jointed connection with each other and together forming a skeleton frame, a flexible water tight cover inclosing said frame, spreader braces for expanding said frame and holding the same 80 expanded, and a hatch providing for ingress and egress to and from the interior of said boat.

75

3. A collapsible boat comprising a substantially cubical center section and wedge-shaped fore and aft end sections jointed to said center section, all of said sections being composed of bars having a jointed connection with each other and together forming a skeleton frame, a flexible water tight cover 90 inclosing said frame, a hatch providing for ingress and egress to and from the interior of said boat, and a hinged and folding seat 95 connected to the interior of said frame.

85

4. A life boat comprising a skeleton frame, a water tight covering therefor, a hatch in the deck of said boat provided with an opening therein, a flexible hood adapted to cover said opening, and a hood clamping frame on said hatch.

100

5. A life boat comprising a skeleton frame, a water tight covering therefor, a hatch in the deck of said boat provided with an opening therein, a flexible hood adapted to cover said opening, a hood clamping frame on said hatch, and means operable from the interior of the boat for moving said clamping frame.

105

In testimony whereof I affix my signature in presence of two witnesses.

WILLIAM R. PARKINSON.
